UNITED STATES PATENT OFFICE.

ALBERT H. MORTON, OF LOWELL, MASSACHUSETTS.

THREAD-BOARD FOR SPINNING, TWISTING, AND LIKE MACHINES.

1,101,876.

Specification of Letters Patent.

Patented June 30, 1914.

Application filed January 21, 1913. Serial No. 743,292.

To all whom it may concern:

Be it known that I, ALBERT H. MORTON, a citizen of the United States, residing at Lowell, in the county of Middlesex and State 5 of Massachusetts, have invented certain new and useful Improvements in Thread-Boards for Spinning, Twisting, and the like Machines; and I do hereby declare the following to be a full, clear, and exact description 10 of the invention, such as will enable others skilled in the art to which it appertains to make and use the same.

The present invention relates to an improvement in thread boards for spinning, 15 twisting and the like machines.

The object of the invention is to reorganize and improve the construction of thread boards, and to this end the invention consists in the thread board hereinafter described and particularly defined in the 20 claims.

In the accompanying drawings illustrating the preferred form of the invention, Figure 1 is an elevation of a thread board 25 with the board in vertical position; Fig. 2 is a sectional plan on the line 2—2 of Fig. 1; Fig. 3 is a section on the line 3—3, Fig. 1; and Fig. 4 is a section on the line 4—4, Fig. 1.

Heretofore, when the doffing rail was 30 lifted, it sometimes happened that some of the thread boards fell over, with the result that when the doffing rail was lowered, the thread boards which had fallen over remained in turned-back position; this required the operative to turn each one of them down separately into normal or operative position.

The present invention contemplates providing 35 means for holding the thread boards in and restoring them to operative position with relation to the doffing rail, or other support, after disturbance therefrom whether in doffing or in piecing, or otherwise.

Referring to the drawings, the thread board 1 carries at its outer end the thread guide or finger 2, and is supported at its inner end upon the thread board support 3 40 which is adapted to be bolted to the doffing rail. The thread board is secured to the thread board support by means of the hinge pintle 4 which is received in ears 5 of the thread board 1 with a driving fit. This 45 pintle is loosely received in the bearings 6 and 7 of the thread board support 3 so as to

turn freely therein. The pintle is embraced by a spring 8 which at one end engages the slot 9 in the pintle and at the other end engages the thread board support 3. The construction is such that when the thread board is lifted it winds up the spring 8 and the lifting is accomplished against the resistance of the spring, so that when the lifting pressure upon the thread board is relieved, the spring returns the thread board to its normal or operative position with relation to the doffing rail.

In Fig. 3 is shown a portion of the thread board and its support, illustrating the position of the left-hand end of the spring 8; Fig. 4 is a similar view looking in the opposite direction, showing the right-hand end of the spring 8 in engagement with the notch 9 in the pintle 4, and both showing the thread board in its normal or operative position. The lugs 10 serve as stops to support the thread board in its normal or operative position, and act to limit the movement of the thread board under the influence of the spring 8 in the downward direction.

The thread board may be supported on a part attached to the doffing rail, as in the illustrated embodiment, or otherwise; so it will be understood that the term "support," 85 as used in the claims, is a comprehensive term indicating any form of support for the thread board.

This invention contributes to facility of attendance because the thread boards tend to hold themselves in operative position and are not required, either by reason of displacement in piecing or in doffing, to be returned to operative position, as they normally maintain their operative position with 90 relation to the doffing rail or the support therefor without any attention on the part of the operative.

The inexpensiveness and simplicity of the invention contribute to its value and utility.

The gist of the invention, broadly considered, resides in providing a thread board with means by virtue of which it is normally maintained in operative position with relation to the doffing rail or other support 105 therefor.

The invention is not limited to the illustrated embodiment thereof.

Having thus described the invention, what is claimed is:—

1. A spinning frame having, in combination, a thread board, a thread board support

upon which the thread board is pivoted, and means tending to turn the thread board on the pivot in the direction to hold it in its normal or operative position thereon, substantially as described.

2. A spinning frame having, in combination, a thread board, a thread board support upon which the thread board is pivoted and a spring connecting the thread board and support tending to turn the thread board in the direction to cause it to assume its normal or operative position thereon, substantially as described.
- 10

3. A spinning frame having, in combination, a thread board, a thread board support upon which the thread board is pivoted, a pintle forming the pivot connecting the thread board and thread board support, and a helical spring mounted upon the pintle and acting to hold the thread board in normal or operative position thereon, substantially as described.

ALBERT H. MORTON.
